VAPOR ELECTRIC DEVICE WITH COOLING COIL SERVING AS HEATING RESISTOR

Harold Winograd, Milwaukee, Wis., assignor to Allis-Chalmers Manufacturing Company, Milwaukee, Wis., a corporation of Delaware

Application February 6, 1948, Serial No. 6,716

20 Claims. (Cl. 250—27.5)

1

This invention relates generally to the manufacture of electric valves and relates particularly to improvements in means for expelling occluded gases therefrom.

An object of the invention is the provision for the expulsion of occluded gases from the elements of an electric valve, a process known as "degassing" or forming, at temperatures at which the atmospheric pressure normally exerted on the valve may exceed the elastic limit of the valve casing.

Another object of the invention is to expel occluded gases from substantially all surfaces of the casing of an electric valve at temperatures at which the atmospheric pressure normally exerted on the valve casing may exceed the elastic limit thereof.

Another object of the invention is to expel occluded gases from an electric valve by providing for the application of heat internally of the valve casing, utilizing for this purpose an integral element of the valve in a capacity other than its primary function.

Another object of the invention is to expel occluded gases from an electric valve by providing for the application of heat internally of the valve casing without introducing auxiliary heating means into the valve casing.

Another object of the invention is the provision for returning heat, theretofore radiated from an electric valve, to the casing of the electric valve for the expulsion of occluded gases therefrom.

Another object of the invention is the provision for heating an internal element of an electric valve without deleteriously affecting the seal between that element and the valve casing.

Another object of the invention is the provision for preventing oxidation of exposed elements of an electric valve during the degassing thereof at elevated temperatures.

The novel features of this invention and how the objects are obtained will appear from this specification and the accompanying drawings showing several embodiments of the invention and forming part of this specification and all the novel features are intended to be pointed out in the claims.

Fig. 1 is a vertical section of an electric valve and vacuum vessel illustrating apparatus embodying the invention.

Fig. 2 is an enlarged vertical section of the fluid tight seal between the electric valve and the vacuum vessel of the apparatus shown in Fig. 1.

2

Fig. 3 is a bottom view of the helical pipe baffle shown in Fig. 1.

Fig. 4 is an enlarged vertical section of one of the fluid cooled electrical terminal connectors and insulated riser of the pipe baffle shown in Fig. 1.

Fig. 5 shows another embodiment, partly in section and partly in elevation, of the apparatus shown in Fig. 1.

Referring to Fig. 1, the apparatus here shown comprises a vacuum tank or vessel 11, into which an electric valve generally designated 12 has been placed for degassing or forming. By the terms "degassing" or "forming" is meant the expulsion of occluded gases from the elements of the electric valve at elevated temperatures. By the term "vacuum vessel" is meant a vessel capable of having its volumetric fluid contents withdrawn therefrom, and thereby at least a partial vacuum formed therein.

The vacuum vessel 11 is substantially cup-shaped, comprising a vertically disposed cylindrical wall 13 partially closed at an upper end thereof by a top disk 14 having an axially disposed circular aperture. The cylindrical wall 13 has the lower end thereof closed by a bottom disk 16. Both the top disk 14 and bottom disk 16 are adjoined to the wall 13 in fluid-tight relation thereto in any suitable manner, as by welding. Since the vessel 11 is required to withstand an overall applied external pressure not exceeding atmospheric pressure at normal operating temperatures, the walls 13 of the cylinder, the top disk 14 and the bottom disk 16 must be constructed of material of appropriate strength, such as steel, and of the proper thickness.

The electric valve 12 shown at least partly inserted within the vacuum vessel 11 is a vapor electric device of the single anode type, and comprises a substantially cylindrical cup-shaped casing 17 which is preferably made of conducting material, such as steel, but which may be made of an insulating material, such as glass. The casing 17 must have a wall thickness sufficient to withstand atmospheric pressure at service temperatures. The casing 17 is closed by a disk-shaped anode plate or cover 18, the casing 17 being dished outward at the rim to form a flange 19 following the peripheral contour of the cover 18. The cover 18 is preferably made of a material such as steel and is sealed in fluid tight relation to the casing 17 by any suitable means, as by welding flange 19 to the cover 18 at the periphery thereof.

As will be apparent in Fig. 1, the cover 18 of

the electric valve 12 is also the cover for the vacuum vessel 11. The cover 18 functions to seal the vessel 11 as follows: Surrounding the aperture in the top disk 14 of the vessel 11 is an upward extending flange 20. As shown in Fig. 2, the flange 20 has an upper face carrying an annular groove into which groove an annular gasket 21, preferably made from a material such as aluminum, is inserted. Since the electric valve 12 is suspended in the vessel 11, the flange 19 is supported on the flange 20 of the top disk 14. The gasket 21 is compressed between the flanges 19, 20 and is retained in place by a clamping ring 22 in the following manner: Referring to Fig. 1, the clamping ring 22 rides on a plurality of circumferentially spaced studs 23 secured to the upper side of the cover 14 of the vessel 11. A nut 24 cooperates with each stud 23 to force the ring 22 against the cover 18 and flange 19, which in turn bear against the gasket 21 to effect a fluid tight connection between the casing 17 of the valve 12 and the vessel 11. When it is desired to remove the electric valve 11 from the vessel 12, it is only necessary to back off the nuts 24 and remove the clamping ring 22 from the studs 23 to disengage the valve 12 from the vessel 11.

The vessel 11 may be fitted with a nest of coaxially disposed cup-shaped heat barriers 25, 26, 27 for protecting the wall 13 thereof from heat radiated by the valve 12, the barriers 25, 26, 27 being arranged in concentric relation about the casing 17 of the valve 11. The barriers 25, 26, 27 are preferably made of a nonoxidizable material having good reflective radiating characteristics, such as stainless steel. As will be noted, the barrier 25 forming the outermost element of the nest of barriers is supported on the bottom disk 16 of the vessel 11 by means of a tube 28 depending from a coaxially disposed well 29 in the bottom of the barrier 25. One end of the tube 28 penetrates the disk 16 in sealed relation thereto; the other end of the tube 28 opens into the well 29 through a suitable opening in the base thereof. The tube 28 has the lower end thereof closed by a cap 30. A conduit 32 connects with a depending portion of the tube 28 and leads to suitable means for evacuating the vessel, the evacuating means being here shown as a rotary vacuum pump 33 driven by an electric motor 34. Suitable heat resistant insulating material, such as rock wool 31, may be introduced into the space between the barrier 25 and the wall 13, the rock wool 31 cooperating with the barriers 25, 26, 27 to retard the transmission of heat from the valve 12 to the wall 13.

Each of the intermediate heat barriers 26, 27 is supported in turn by the barrier adjacent and external thereto, the necessary support for each barrier being furnished by circumferentially spaced legs 35, attached to the bases thereof. Spacing guides 36 are provided for each of the barriers at the upper end thereof, each guide 36 extending radially from its associated barrier and being attached thereto by any suitable means, as by welding. Sufficient space is allowed between the end of each guide and the next adjacent barrier to allow for radial expansion of the intermediate barrier under the influence of heat. Performing a similar function, a depending annular flange 37 is mounted on the underside of the top disk 14 to maintain the outermost barrier 25 in substantially coaxial alignment relative to the wall 13 of the vessel 11. It will be apparent that by maintaining the outermost bar-

rier 25 in coaxial alignment with the vessel 11, the innermost barrier 27 is assured of being in correct alignment with aperture in the top disk 14 of the vessel 11.

The electric valve 12 which depends into the innermost barrier 27 comprises, in addition to the casing 17 and cover 18 hereinbefore described, a number of conductive and insulating elements which are briefly set forth as follows:

The cover 18 carries a main anode 38 which depends therefrom into the casing 17. The anode 38 is electrically connected to a cylindrically-shaped conductor 39 coaxially mounted within a sleeve 41 extending upward from the cover 18. Means for sealing the conductor 39 against the cover 18 comprises a laminated vitreous seal assembly 42, which, in addition to providing a fluid tight seal, also electrically insulates the conductor 39 from the cover 18 and furnishes the conductor 39 with the necessary mechanical support. As shown, the conductor 39 screws into a tapped axial bore of the anode 38. A portion of the conductor 39 which extends above the cover 18 is fitted with a cooling radiator 43 for dissipating heat generated by the anode 38 during normal operation of the valve 12. The anode 38 is generally cylindrical in shape and may be made of any suitable conductive material, preferably graphite.

As assembled prior to degassing, the electric valve 12 is without cathode means since the degassing process hereinafter to be described would result in the involuntary withdrawal of the cathode means from the casing 17. After the degassing process, cathode means comprising a pool of mercury or other suitable vaporizable material, indicated by a dotted line at 44 in Fig. 1, is added to the valve 12 and assumes a position at the bottom 45 of the casing 17 in a conductive relation thereto. An upward extending annular insulator 46, known as a cathode ring and preferably made of a material such as quartz, bounds the active surface of the mercury. The insulator 46 is coaxially mounted in any suitable manner on a radially notched disk 47 which in turn is carried by the bottom 45 of the casing 17.

A control electrode or grid 48 is arranged in spaced proximity to the anode 38 for controlling the flow of current between the anode 38 and cathode 44. The grid 48 may be made of any suitable conductive material such as graphite, and is preferably basket-shaped to follow the contour of the anode 38. Numerous perforations are provided in the side and bottom walls of the grid 48 to permit the passage of the arc discharge between anode 38 and cathode 44 and to permit the radiation therethrough of heat from the surface of the anode 38 during normal operation of the valve 12. The grid 48 is supported in any suitable manner, preferably from the cover 18 by means of a plurality of depending segmented insulators 49. A control potential may be impressed upon the grid 48 through an insulated fluid tight connection, not shown, penetrating the cover 18.

The paths of the arc discharge between anode 38 and cathode 44 and of the flow of material vaporized from the cathode 44 during normal operation of the valve 12 are controlled by means of a disk shaped baffle 51 axially disposed below the grid 48, and by means of a fluid cooled pipe baffle 52 which encircles the anode 38 and grid 48 and extends below the disk-shaped baffle 51. The baffle 51 is preferably made of a conductive material such as graphite. The pipe baffle 52 is

preferably made of a conductive material, such as stainless steel, which is not attacked by water or by mercury, and serves to cool the valve 12 during service operation thereof.

The pipe baffle 52 is preferably of circular cross section forming a passage for the flow of water or other cooling fluid. The baffle 52 is preferably assembled as a unit comprising two helixes of pipe joined at one end, as shown in Fig. 3, by an interconnecting tube 53, and having the turns of the respective helixes interleaved in spaced relation. By constructing the pipe baffle 52 in this fashion, a noninductive winding is created. However, the pipe baffle 52 may be wound from a single helix to form an inductive winding if so desired. The turns of the pipe baffle 52 are insulated one from the other by a plurality of circumferentially spaced spool-shaped insulators 50 which preserve the rigidity of the pipe baffle 52 and prevent the sagging of individual turns thereof upon the application of heat thereto.

The free ends of the helixes of the pipe baffle 52 terminate in upward extending risers 54 for leading the pipe baffle through the cover 18. Risers 54 penetrate the cover 18 diametrically and are respectively sealed thereagainst by means of a flexible composite vitreous and metal seal assembly 55, as shown in Fig. 4. In addition to sealing the risers 54 in fluid tight relation against the cover 18, the seal assemblies 55 electrically insulate the pipe baffle 52 from the cover 18 and casing 17. To protect the seal assemblies 55 against breakage, each seal assembly 55 is surrounded by an upward extending sleeve 56 mounted in any suitable manner on the cover 18. An annular insulator 57 closes the sleeve 56 and electrically insulates the riser 54 therefrom. An annular gland 58 cooperates with the insulator 57 to seal the insulator 57 against the riser 54.

Referring to Fig. 1 it will be observed that at the lower end of the pipe baffle 52, the interconnecting tube 53 joining the helixes provides a support for the disk-shaped baffle 51. In turn, the baffle 51 supports a graphite ignition-excitation anode 59 insulated therefrom. A suitable potential may be impressed on the anode through an insulated lead-in connection 61. Below the cathode 44 a device 62 of any suitable type, such as of the electro-magnetic type, electrically and mechanically momentarily connects the cathode pool 44 with the ignition anode 59 when it is desired to ignite an arc at the cathode during normal operation.

A funnel-shaped shield or gutter 63 supports the pipe baffle 52, the gutter 63 being suspended by means of a plurality of axially depending rods 64, only one of which is here shown, from an inverted pan shaped shield 65 located near the top of the casing 17. The shield 65, which extends over and around the upper portion of the grid 48, and is penetrated by the risers 54 in insulated relation thereto, is itself suspended from the cover 18 and insulated from the grid 48 and cover 18 by means of the segmental insulators 49.

The electric valve 12, subsequent to assembly and prior to normal service operation, must be conditioned for the passage of current between the anode 38 and cathode 44, the conditioning process comprising degassing or forming, as well as evacuating. In other words, it is necessary to expel occluded gases from the elements of the valve 12, as well as expel free gases from the interior of the casing 17 before the valve 12 can normally function. The term "gases" includes actual gases, as well as moisture, grease, and

other vaporizable impurities normally present, which would hinder the maintenance of the required vacuum in normal operation over an extended period. A method of expelling occluded gases from the elements of the valve 12 is to heat the elements at an elevated temperature in a vacuum. Although the pipe baffle 52 has the primary function of providing a means for circulating cooling fluid for the removal of heat radiated by the arc and elements of the valve 12 when the valve 12 is normally operated in service, the pipe baffle 52 may be utilized in a secondary capacity to heat the elements of the valve during degassing. This may be done effectively by employing the pipe baffle 52 as a resistance heater. Accordingly, means for supplying a heating current to the pipe baffle 52, the means being here shown schematically as an alternating current generator 66 and associated power transformer 67 having a tapped secondary winding, is connected to the risers 54 through terminal connectors 68. Although a low or intermediate frequency generator and transformer is here shown, the means for supplying a heating current to the pipe baffle 52 may otherwise comprise either a high frequency generator and transformer or a direct current generator.

Referring to Fig. 4, the terminal connector 68 here shown comprises a straight cylindrical tube, having an axially extending bore therein. The connector is made of conductive material and has a flared extension 71 closing the bore at one end. The connector 68 together with a contact ring 72 having a plurality of segments is coaxially inserted into the passage of the riser 54. The ring 72 engages a threaded portion 73 of the connector 68 lying directly above the flared extension 71 and extends coaxially below the threaded portion 73 to embrace a substantial portion of the extension 71. It will be apparent that the segments of the ring 72 are shaped at their outer periphery to follow the contour of the inner wall of the riser 54, and at their inner periphery to follow the contour of the connector 68. By turning the connector 68 in a predetermined direction about the linear axis thereof, the segments of the ring 72 are forced to move radially outward against the wall of the riser 54. The resulting wedging action of the ring 72 against the inner wall of the riser 54 establishes a positive electrical connection between the connector 68 and the pipe baffle 52. By wedging the connector 68 against the riser 54 at a point a material distance below the composite seal assembly 55, the seal assembly 55 is afforded relative protection from the heat generated in the pipe baffle 52 upon the passage of current therethrough. The segments of ring 72 are spaced from each other to define a passage for the removal of air and other gases from the interior of the pipe baffle 52.

Above the riser 54, the connector 68 is closed at the end thereof by a cap 74 through which a first tube 75 passes. The tube 75 extends downward through the bore for substantially the length thereof to form a passage for the flow of cooling fluid. A second tube 76 penetrates the cap 74 at right angle to the first tube 75 to connect with an annular space in the bore surrounding the first tube 75. The tubes 75, 76 are sealed to the cap 74 by any suitable means, as by welding the tubes 75, 76 to the cap 74, and provide respectively an entrance and an exit for circulation of cooling fluid. The fluid enters the connector 69 preferably through the axially disposed first tube 75,

flows through the annular space surrounding the tube 75, and leaves through the second tube 76. Directly below the cap 74 is a lug 77 to which the transformer 67 is connected. Below the lug 77 and embracing the connector 68 is a collar 78 having a stepped axial bore adapted to receive in a close fit the upward extending riser 54 and connector 68. Means for sealing the riser 54 and connector 68 in fluid tight relation with the collar 78 comprises a top annular gasket 79 and a bottom annular gasket 81 cooperating respectively with the collar 78 and the connector 68 and the collar 78 and the riser 54, and retained in place by means of respective glands 82, 83 bolted to the collar 78. The collar 78 of one of the connectors 68 has a radially extending bore intercepting the axial bore immediately above the end of the riser 54. A tube 84, only a portion of which is shown in Fig. 4, is inserted into a portion of the radial bore of the collar 78 and retained therein by means of an annular gasket 85 and associated cooperating gland 86. As shown in Fig. 1, the tube 84 leads to evacuating means, here shown as a rotary vacuum pump 87 driven by a suitable electric motor 88. By means of the pump 87 a vacuum can be established in the interior of the pipe baffle 52 to prevent oxidation thereof during the employment of the pipe baffle 52 as a resistance heater, the gases being withdrawn through the annular space surrounding the connector 68 and through the passage defined by the segments of ring 72. The gases flow through the tube 84. The other connector 68 is similar except that there is no opening in the collar 78 for connection to an evacuating means.

Evacuating means is also provided for evacuating the casing of the electric valve and may comprise, as here shown, a molecular pump 89 using a suitable vaporizable material, and a rotary vacuum pump 91 driven by a suitable electric motor 92.

Having described and illustrated apparatus suitable for degassing an electric valve, it is now meet that the assembly and operation thereof be described, particularly with reference to the type of valve here shown.

Let us assume for the purposes of illustration, that the valve 12 shown in Fig. 1 has just been assembled and suspended in the vacuum vessel 11 for degassing. Digressing for the moment, it should be noted that a portion of the electromagnetic device 62, namely, a coil, not shown, has been disconnected and removed from the valve casing 17 so as not to expose that portion of the device 62 to the heat applied during degassing. The clamping ring 22 is fastened down to securely seal the cover 18 of the valve 12 to the vessel 11, thereby making the vessel 11 fluid tight. The valve 12 is now ready for connection to the power transformer 67. The connecting terminals 68 are inserted into the risers 54 and respectively wedged therein as hereinbefore described. The collar 78, which is already in engagement with the exposed upward portion of the connector 68 is made fast to both the riser 54 and the connector 68 by adjusting the glands 82, 83 to insure a fluid tight seal between the riser 54 and the collar 78 and between the collar 78 and the connector 68.

Finally, with the connection of the power transformer 67 to the lugs 77 of the connectors 68, the 70 electrical heating circuit is complete. The flow of current upon subsequent energization of the circuit is from the transformer 67 through the pipe baffle 52 and back to the transformer 67. Since the seal assemblies 55 may be injured by

the application of high temperatures necessary for degassing the valve, cooling means, such as a cooling fluid from a suitable source, not shown, is circulated through the connectors 68 at all such times that a current is circulated through the pipe baffle 52. By providing cooling means for the connectors 68, the heat generated by the pipe baffle 52 and connectors 68 during the operation of the pipe baffle 52 as a resistance heater is prevented from reaching and damaging the seal assemblies 55.

A final step in the assembly is to connect the vacuum pump 87 to the pipe baffle 52 through the tube 84 and one of terminals 68, and to connect the remaining vacuum pumps 89, 91 to the casing of the valve 12.

Having completed the assembly of the apparatus, the degassing process or operation may begin.

The vacuum pumps 33, 89, 91, 87 are started and after the desired vacuum is reached in each of the components of the apparatus; namely, the casing 17, pipe baffle 52 and vacuum vessel 11, current is gradually or abruptly applied to the pipe baffle 52. The degree of vacuum in each component may be measured by any suitable known measuring means such as a hot wire or McLeod gage, not shown, the vacuum measuring means being here omitted because it forms no part of the invention.

The temperature generated in the pipe baffle 52 may be controlled by changing the taps of the power transformer 67 to vary the voltage and give the desired value of heating current. The transformer 67 serves as a current source to supply current to the coils of the pipe baffle 52 and causes the coils to reach a temperature at which occluded gases are given up, not only by the pipe baffle 52 but also by the other elements contained in the casing of the valve 12. The evacuating means for the casing, here shown as pumps 89, 91, cooperate with the current source 67 in removing the occluded gases from the valve elements, which include the pipe baffle 52 and the casing 17.

It has been found that the apparatus performs most effectively to expel occluded gases from the elements of the valve at a mean pipe baffle temperature range of from 800 to 900° C. At this temperature range the elements of the valve are found to give up a large portion of the gases occluded therein.

After the required degree of degassing has been obtained, the electrical heating circuit is opened and the valve 12 allowed to cool off gradually while the pumps 89, 91 continue to operate. At a predetermined intermediate valve temperature the cathode vaporizable material is introduced into the casing 17 by any suitable means, not shown. When the temperature of the valve 12 has reached a sufficiently low predetermined value the evacuation connection to the pumps 89, 91 is sealed off. The valve 12 is now hermetically sealed and the connection to the vacuum pumps 89, 91 may be removed. If thereafter, the valve is operated in service at a temperature substantially lower than the degassing temperature, the original vacuum can be maintained without having to further evacuate the casing of the valve at periodic intervals.

The degassing at high temperatures of elements of the valve which in service operate at relatively low temperatures, e. g., the casing 17 and the pipe baffle 52, leads to a most important result when the valve is placed in service. For 75 then these same elements, the casing 17 and pipe

baffle 52 being here representative of such elements, will act as highly effective absorbers of gases given off by the other elements of the valve which in service operate at high temperatures, e. g., the anode 38, grid 48, baffle 51 and excitation anode 59. Therefore, by degassing the valve as hereinbefore described at elevated temperatures, a good vacuum can be maintained over an extended period in the valve after the sealing thereof, even though some gases are given off by these elements, namely, grid, anode, etc. which operate at high temperatures during service operation.

When the pipe baffle 52 and elements of the electric valve 12 are heated to a temperature of from 800 to 900° C., the casing 17 of the valve 12 reaches a dull red heat. It is well known that regardless of the type of steel which may be used in the casing 12, the yield point and tensile strength thereof are greatly reduced at such temperatures as compared with the yield point and tensile strength of the same steel at 20° C. Reference is made to the U. S. Bureau of Standards, circular C447, "Mechanical Properties of Metal Alloys," wherein values of yield point and tensile strength for steels of various compositions are given as a function of the temperature. For example, a steel containing 0.15 carbon has a yield point of 42,000 lbs. per square inch at 27° C. (80° F.) as compared with only 3,800 lbs. per square inch at 760° C. (1400° F.). It follows that a casing, as here shown, made of steel having a 0.15 carbon content, if constructed with a wall thickness having a reasonable factor of safety under atmospheric pressure at 20° C., would collapse under the same pressure at 800° C. For this reason the valve 12 is contained, as here shown, in the evacuated vessel 11, before being subjected to high temperatures. If no vacuum vessel surrounded the valve during degassing thereof, it would be necessary to thicken the casing walls substantially beyond their present thickness to withstand the atmospheric pressure at elevated temperatures. From a commercial and engineering point of view, such a thickening of the casing walls would be costly and impractical. Therefore, the vacuum vessel 11 is utilized to protect the casing of the valve 12 from destructive external pressures during degassing.

The walls 13 of the vacuum vessel 11 must also be protected, during the forming of the valve, from heat radiated by the casing 17, since the heat radiated may raise the temperature of the walls 13 of the vessel 11 with a subsequent reduction in the yield point thereof below a safe value. Such protection from heat radiated by the valve 12 is adequately afforded through the nest of heat baffles 25, 26, 27 and insulation 31 hereinbefore described, the baffles 25, 26, 27 returning a large proportion of the radiated heat to the casing 17 of the valve 12. In this way not only is the vacuum vessel 11 protected but the heat loss is reduced. Since a lesser amount of heat is required, the current in the pipe baffle 52 may be reduced to a smaller value.

Although the elements of the valve 12 may be safely raised to a temperature of 800 to 900° C. to expel the occluded gases therefrom, the composite metal and vitreous seals 42, 55 in the cover 18 of the valve 12 would be damaged at such temperatures. Accordingly, the valve 12 is inserted in the vacuum vessel 11 in such a manner, as here shown in Fig. 1, to leave the cover 18 and the seals 42, 55 exposed to the cooling influence of the ambient air.

If more positive cooling protection is desired, or, if it is desired to protect the exterior of the cover 18 and the metal of the seals 42, 55 from the undesirable effects of oxidation at elevated temperatures, or both, the valve 12 may be further enclosed by means of an auxiliary cup-shaped vacuum tank 93, as shown in Fig. 5, which is placed in an inverted position over the cover 18 of the valve and sealed thereto in fluid tight relation by means of a suitable annular gasket 94 interposed between the rim of the tank 93 and the cover 18. A radially extending flange 95 forming part of the tank 93 and having a plurality of circumferentially spaced holes to receive the studs 23 of the vacuum vessel 11 cooperates with nuts 24 to retain the tank 93 in position atop the cover 18. The tank 93 is penetrated by the connectors 68 and the conduit leading to the vacuum pumps, not shown. Appropriate annular gaskets 96 are provided at all such points of penetration of the tank, the gaskets 96 being retained in fluid tight relation thereto by means of annular glands 97 cooperating therewith and secured to the tank 93 in any suitable manner, as by bolts, not shown.

A reservoir 98 containing nitrogen or other suitable inert gas under pressure is connected through a stopcock 99 to the tank 93 at one side thereof, and a suitable evacuating means, here shown as a rotary vacuum pump 100 driven by an electric motor 101, is connected through a conduit to the other side of the tank 93. The riser 54 communicates directly with the interior of the tank 93.

As constructed and arranged the tank 93 offers means for protecting the seals 42, 55 and other exposed elements from oxidation, the protection being afforded by either of one of two methods. In the first method the tank 93 is evacuated, the petcock 99 being in the shut-off position. Since the pipe baffle 52 opens into the tank 93, the pipe baffle 52 is likewise evacuated by the pump 100. Any gases which might contribute to oxidation of the exposed elements as well as to oxidation of the interior of the pipe baffle 52 are thus removed. In the second method the gases in the tank 93 and pipe baffle 52 are withdrawn therefrom by means of the pump 100 and inert gas which is contained in the reservoir 98 is introduced therein. In the second method the stopcock 99 is in the open position. The introduction of an inert gas in contact with the pipe baffle 52 and other exposed elements of the valve 12, which elements are at an elevated temperature, prevents the oxidation thereof during the degassing of the valve 12. If cooling of the seals 42, 55 mounted on the cover 18 of the valve 12 is desired, over and above the cooling already provided by the cooling fluid flowing in the connectors 68, the inert gas may be introduced continually into the tank 93 and exhausted through the petcock 102 during the forming of the valve 12. Thus a constant stream of cool inert gas is circulated in proximity to the seals 42, 55, conductor 39 and radiator 43.

The tank 93 and the vessel 11 thus comprise first and second vacuum vessels into which one and another portion of the valve 12 is inserted, the vessels 11, 93 being sealed to the valve 12 and evacuated as hereinbefore described.

Although but two embodiments of the present invention have been herein illustrated and described, it will be apparent to one skilled in the art that various changes or modifications, singly or collectively, may be made therein without de-

parting from the spirit of the invention or from the scope of the appended claims.

It is claimed and desired to secure by Letters Patent:

1. In combination, an electric valve comprising an evacuated casing and conductive elements disposed within said casing, conducting means for cooling said valve disposed within said casing adjacent to said elements, and means including a source of current connected to said conducting means for the heating thereof to heat said elements of said electric valve to expel occluded gases therefrom.

2. In combination, an electric valve comprising an evacuated casing and conductive elements disposed within said casing, conducting means forming a passage for the flow of fluid for cooling said valve disposed within said casing adjacent to said elements, and means including a source of current connected to said conducting means for the heating thereof to heat said elements of said electric valve to expel occluded gases therefrom.

3. In combination, an electric valve comprising an evacuated casing, conducting means forming a passage for the flow of fluid for cooling said valve disposed within said casing, and means including a source of current connected to said conducting means for the heating thereof to expel occluded gases from said conducting means.

4. In combination, an electric valve comprising an evacuated casing, conducting means having a wall portion defining a passageway for the flow of fluid therethrough for cooling said valve, said conducting means being disposed within said casing, and means including a source of current connected to said conducting means for the heating thereof to expel occluded gases from said passageway.

5. In combination, an electric valve comprising a sealed casing and conductive elements disposed within said casing, evacuating means connected to said casing for fluid evacuation thereof, conducting means forming a passage for the flow of fluid for cooling said valve disposed within said casing adjacent to said elements, and a source of heating current connected to said conducting means for heating said conducting means to heat said elements of said valve, said current source cooperating with said evacuating means to remove occluded gases from said elements.

6. In combination, a vessel, an electric valve comprising a sealed casing and elements disposed within said casing, at least a portion of said casing being inserted in said vessel, means for sealing said vessel against said casing to prevent the ingress of fluid to said vessel, evacuating means connected with said vessel and said casing for fluid evacuation thereof, a conductor disposed within said casing, and a source of current connected to said conductor for supplying heating current thereto to heat said elements of said electric valve, said current source cooperating with said evacuating means to remove occluded gases from said elements, said conductor, and said casing.

7. In combination, a vessel comprising a wall portion, insulating means including heat reflecting means disposed within said vessel in spaced relation with said wall portion, an electric valve comprising a sealed casing, and elements disposed within said casing, at least a portion of said casing being inserted in said vessel, means for sealing said vessel against the ingress of fluid, evacuating means connected with said vessel and said casing for fluid evacuation thereof, a con-

ductor disposed within said casing, a source of current connected to said conductor for supplying heating current thereto to heat said elements of said valve, said reflecting means shielding said vessel against heat radiated from said casing, and said current source cooperating with said evacuating means to remove occluded gases from said elements and said casing.

8. In combination, an electric valve comprising a casing and elements disposed within said casing, conducting means having a wall defining a passage for the flow of fluid for cooling said casing and said elements, said conducting means disposed within said casing adjacent to said elements, means for leading said conducting means through said casing including means for establishing a fluid tight seal therebetween, a source of heating current, means for connecting said conducting means to said current source to heat said conducting means to heat said elements and said casing to expel occluded gases therefrom, said connecting means including a connector coaxially introduced into said passage of said conducting means and connected to said wall thereof within said casing at a material distance from said sealing means to prevent the transmission of deleterious heat from said conducting means to said sealing means, said connector comprising a portion having a passageway for the flow of cooling fluid therethrough, and another portion engaging said wall of said conducting means to define a passage, and evacuating means connected with said passage and said casing, said evacuating means cooperating with said source to remove occluded gases from said wall of said conducting means and from said casing and said elements of said valve.

9. In combination, an electric valve comprising an evacuated casing and elements disposed within said casing, conducting means having a wall defining a passage for the flow of fluid for cooling said valve, said conducting means disposed within said casing adjacent to said elements, means for leading said conducting means through said casing including means for establishing a fluid tight seal therebetween, a source of heating current, means for connecting said conducting means to said current source for heating said conducting means to heat said elements of said valve to expel occluded gases therefrom, said connecting means including a connector coaxially introduced into said passage of said conducting means and connected to said wall thereof within said casing at a material distance from said sealing means to prevent the transmission of deleterious heat from said conducting means to said sealing means.

10. In combination, an electric valve comprising an evacuated casing and elements disposed within said casing, conducting means having a wall defining a passage for the flow of fluid for cooling said valve, said conducting means disposed within said casing adjacent to said elements, means for leading said conducting means through said casing including means for establishing a fluid tight seal therebetween, a source of heating current, means for connecting said conducting means to said current source for heating said conducting means to heat said elements of said valve to expel occluded gases therefrom, said connecting means including a connector coaxially introduced into said passage of said conducting means and connected to said wall thereof within said envelope at a material distance from said sealing means to prevent the transmission of deleterious heat from said conducting means

to said sealing means, said connector comprising relatively movable members so constructed and arranged as to wedge one of said members against said wall of said conducting means upon a pre-determined relative movement of another of said members to effect a positive electrical connection between said current source and said conducting means.

11. In combination, an electric valve comprising an evacuated casing and elements disposed within said casing, conducting means having a wall defining a passage for the flow of fluid for cooling said valve, said conducting means disposed within said casing adjacent to said elements, means for leading said conducting means through said casing including means for establishing a fluid tight seal therebetween, a source of heating current, means for connecting said conducting means to said current source for heating said conducting means to heat said elements of said valve to expel occluded gases therefrom, said connecting means including a connector coaxially introduced into said passage of said conducting means and connected to said wall thereof within said envelope at a material distance from said sealing means to prevent the transmission of deleterious heat from said conducting means to said sealing means, said connector having a passageway for the flow of cooling fluid therethrough, and evacuating means connected with said conducting means and cooperating with said current source to remove occluded gases from said wall of said conducting means.

12. In combination, an electric valve comprising an evacuated casing and elements disposed within said casing, conducting means having a wall defining a passage for the flow of fluid for cooling said valve, said conducting means disposed within said casing adjacent to said elements, means for leading said conducting means through said casing including means for establishing a fluid tight seal therebetween, a source of heating current, means for connecting said conducting means to said current source for heating said conducting means to heat said elements of said valve to expel occluded gases therefrom, said connecting means including a connector coaxially introduced into said passage of said conducting means and connected to said wall thereof within said envelope at a material distance from said sealing means to prevent the transmission of deleterious heat from said conducting means to said sealing means, said connector comprising a portion having a passageway for the flow of cooling fluid therethrough, and another portion engaging said wall of said conducting means to define a passage, and evacuating means connected to said passage and cooperating with said current source to remove occluded gases from said wall of said conducting means.

13. In combination, a vessel comprising a wall portion, an electric valve comprising a sealed casing and elements disposed within said casing, at least a portion of said casing being inserted in said vessel, heat reflecting means disposed within said vessel intermediate said wall portion and said casing, means for sealing said vessel against the ingress of fluid, evacuating means connected with said vessel and said casing for fluid evacuation thereof, a conductor disposed within said casing, a source of current connected to said conductor for supplying heating current thereto to heat said elements of said valve, said reflecting means shielding said vessel against heat radiated from said casing, and said current source cooperating

with said evacuating means to remove occluded gases from said elements, said conductor, and said casing.

14. In combination, a vessel comprising a wall portion, an electric valve comprising a sealed casing and elements disposed within said casing, at least a portion of said casing being inserted within said vessel, insulating means disposed in said vessel adjacent said wall portion, reflecting means disposed within said vessel intermediate said wall portion and said casing, means for sealing said vessel against the ingress of fluid, evacuating means connected to said vessel and said casing for fluid evacuation thereof, a conductor disposed within said casing, a source of current connected to said conductor for supplying heating current thereto to heat said elements and said casing, said reflecting means cooperating with said insulating means to shield said wall portion of said vessel from heat radiated from said casing, and said current source cooperating with said evacuating means to remove occluded gases from said elements and said casing.

15. In combination, a vessel comprising a wall portion, an electric valve comprising a sealed casing and elements disposed within said casing, at least a portion of said casing being inserted in said vessel, insulating means disposed within said vessel intermediate said wall portion and said casing, means for sealing said vessel against the ingress of fluid, evacuating means connected with said vessel and said casing for fluid evacuation thereof, a conductor disposed within said casing, a source of current connected to said conductor for supplying heating current thereto to heat said elements of said valve, said insulating means shielding said wall portion of said vessel against heat radiated from said casing, and said current source cooperating with said evacuating means to remove occluded gases from said elements, said conductor, and said casing.

16. In combination, a vessel comprising a wall portion, insulating means including heat reflecting means disposed within said vessel in spaced relation with said wall portion, an electric valve comprising a casing and elements disposed within said casing, at least a portion of said casing being inserted in said vessel, means for sealing said vessel against the ingress of fluid, evacuating means connected with said vessel and said casing for fluid evacuation thereof, a conductor disposed within said casing, and a source of current connected to said conductor for supplying heating current thereto to heat elements of said valve, said reflecting means shielding said vessel against heat radiated from said casing and said current source cooperating with said evacuating means to remove occluded gases from said elements, said conductor, and said casing.

17. In combination, a vessel, an electric valve comprising a sealed casing, and elements disposed within said casing, at least a portion of said casing being inserted in said vessel, means for sealing said vessel against the ingress of fluid, evacuating means connected with said vessel and said casing for fluid evacuation thereof, a conductor disposed within said casing, and a source of current connected to said conductor for supplying heating current thereto to heat elements of said electric valve, said current source cooperating with said evacuating means to remove occluded gases from said elements, said conductor, and said casing.

18. In combination, an electric valve comprising an evacuated casing and conductive elements

15

disposed within said casing; conducting means forming a passage for the flow of fluid for cooling said valve disposed within said casing adjacent to said elements, means for leading said conducting means through said casing including sealing means cooperating with said conducting means and said casing, a source of heating current, and fluid cooled means connecting said current source with said conducting means for supplying heating current thereto to heat said elements of said valve to expel occluded gases therefrom, said fluid cooled means connecting said source to said conducting means within said casing at a point materially distant from said sealing means to prevent the transmission of deleterious heat from said conducting means to said sealing means.

19. In combination, a vessel, an electric valve comprising an evacuated casing, and conductive elements disposed within said casing, at least a portion of said casing being inserted in said vessel, means for sealing said vessel against the ingress of fluid, evacuating means connected with said vessel and said casing for fluid evacuation thereof, and heating means within said vessel to heat said elements of said valve, and cooperating with said evacuating means to remove occluded gases from said elements and said casing.

16

20. In combination, a first vessel, a second vessel, an electric valve comprising a sealed casing and elements disposed within said casing, at least a portion of said valve being inserted in said first vessel, and at least another portion of said valve being inserted in said second vessel, means for sealing said vessels to said casing to prevent the ingress of fluid to said vessels, evacuating means connected with each of said vessels and said casing for fluid evacuation thereof, a conductor disposed within said casing, and a source of current connected to said conductor for supplying heating current thereto to heat said elements of said electric valve, said current source cooperating with said evacuating means to remove occluded gases from said elements, said conductor, and said casing.
